FLUID DISPENSING APPARATUS

Bertram T. Perkins, Chicago, Ill.

Application October 4, 1939, Serial No. 297,798

8 Claims.

(Cl. 225—21)

This invention relates to a fluid dispensing apparatus and more particularly to a dispensing line through which fluid is adapted to flow by gravity and wherein the flow of the fluid through the line is under control of a valve automatically operable to cause stopping of dispensing when an exact unit quantity of fluid has been dispensed.

Another object of this invention resides in providing a coin controlled valve operating mechanism which is constructed and arranged to start the dispensing operation and thereafter to cause the automatic stopping of dispensing when an exact unit quantity of fluid has been dispensed.

Another object of this invention resides in the provision of a fluid dispensing apparatus in combination with a cup vending apparatus, wherein instrumentalities are provided for resetting the valve operating mechanism of the fluid dispensing line to locked condition prior to the initiation of a subsequent dispensing operation.

Another object of this invention is to provide a fluid dispensing apparatus especially suited to use with a device for vending a plurality of differently branded fluid products in combination with a cup vending apparatus.

Yet another object of this invention resides in the provision of a novel type of coin controlled locking mechanism, per se, in which the coin, after deposit in the usual coin receiving slot, may be intercepted and returned to the operator under certain conditions.

Yet another object of this invention resides in the provision of a novel type of locking mechanism wherein operation of a selected fluid dispensing unit in a battery or plurality of such units will automatically prevent operation of any other unit of the battery.

With the above and other objects in view, as will be apparent, this invention consists in the construction, combination and arrangement of parts, as hereinafter more fully described, claimed and illustrated in the accompanying drawings, wherein:

Fig. 1 is a front view of a vending machine embodying a plurality of fluid dispensing units selectively operable under control of a coin controlled cup vending device.

Fig. 2 is an end view of the machine shown in Fig. 1.

Fig. 3 and Figs. 4 and 5 are enlarged fragmentary detail front views of the locking means adapted to control selective operation of the fluid dispensing units, showing such means in respectively different positions.

Fig. 6 is an enlarged fragmentary detail rear

view, with a part of the cup dispensing unit omitted, to show interior parts of the present apparatus.

Fig. 7 is an enlarged fragmentary end view of the parts shown in Fig. 6, including the cup dispensing unit.

Figs. 8, 9 and 10 are fragmentary views of the coin operated mechanism, on a further enlarged scale, showing the cup dispenser operating means and associated parts in different positions.

Fig. 11 is a vertical cross section, also enlarged, of the present apparatus, showing the liquid dispensing mechanism in elevation.

Fig. 12 is a vertical sectional view taken on line 15 12—12 of Fig. 11.

For the purpose of illustrating the features of this invention, the apparatus thereof is disclosed in the drawings as including a plurality of selectively operable units for the dispensing and vending of various commercially known and branded fluid products in combination with a coin operated cup vending unit. As will appear hereinafter, locking mechanism adapted to prevent operation of the liquid dispensing mechanism is controlled by the operating mechanism of the cup dispensing unit, and under such control, the locking mechanism will permit operation of a selected liquid dispensing unit while simultaneously keeping the other liquid dispensing units in locked condition. Each liquid dispensing unit is identical in structure and operation with the other units and it will therefore suffice, in the following description thereof, to consider only a single unit. Obviously, the number of such fluid dispensing units may be greater or less and of modified construction relative to those shown and described herein, without departing from the principles of this invention.

The apparatus of this invention may be conveniently assembled on an upright panel or base plate 10 secured to and enclosed by a casing or cabinet 12 of any desired design or character. As shown, the cabinet 12 has a front wall hinged as at 14 to a fixed support or pedestal 16, so as to permit the wall and the plate 10, with its apparatus, to be tipped forwardly and downwardly (as per dotted line showing of Fig. 2) for the purpose of providing easy access to the parts of the apparatus. The cabinet front wall is, of course, normally secured and locked in closed upright position as shown in full lines of Fig. 2.

The cup dispensing unit has been illustrated as applied to a generally conventional type of individual paper cup vending or dispensing unit, 55 which includes an upstanding holder 18 provid-

ing a housing for a plurality of nested paper cups dischargeable through a mouth 15 of the holder, and an operating lever 17 which is maintained in normally inoperative position (i. e., toward the left as viewed in Fig. 8) by a retrieving spring (not shown) and operative through suitable mechanism to successively select and discharge an individual cup. The holder 15 and its associated parts, are preferably supported on a bracket 18 fastened as at 19 on the rear face of the frame 10.

A rotatable shaft 20, having bearing support in the frame 10 and a supplemental mounting plate 21, is adapted to protrude forwardly through a suitable opening in the front wall of the cabinet 12 for the reception of a handle 22. To the portion of the shaft 20 intermediate the rear face of the frame 10 and the mounting plate 21 is keyed a coin conveyor disk 23 which is detailed in Figs. 8, 9 and 10. The periphery of the disk 23 is provided with a coin chute or groove 24 within which a coin 25 may be sustained in upright position, and a relatively shallow locking recess or groove 26. Shoulders 27 and 28 at each end of the groove 26 coact with a clasp or locking pin 29 to limit rotation of the disk 23 and the shaft 20. The pin 29 is carried by a locking link 30, pivoted as at 31 on the mounting plate 21, which link is normally urged into position by a spring 32 to assume a position to dispose the pin 29 in operative relation to the groove 26.

As shown in Fig. 10, the coin chute 24 is thus arranged immediately below and in vertical alignment with the outlet 33 of a conventional coin receiving and ejecting mechanism rigidly carried on the frame 10. Accordingly, the chute 24 acts as a stop for a coin discharged from said coin outlet 33, and is adapted to hold the coin 25 directly above the shaft 20, with a portion of the coin protruding beyond the shoulder 27 of the groove 26 and beyond the periphery of the disk 23. On turning the shaft 20 and the disk 26 in counterclockwise direction (as viewed in Fig. 8) but clockwise when viewed from the front of the apparatus, the coin 25 will cam the locking pin 29 upwardly and away from the groove 30 to permit the disk 26 and coin 25 to be turned past the pin 29 and to finally tip or dump the coin 25 into a suitable depositary.

A protruding pin 34 on the face of the disk 23 engages the edges of a slot 35 formed in a cup ejector arm 36 rotatively disposed on the shaft 20 adjacent the forward face of the disk 23, so that rotation of the shaft 20 forces the arm 36 to rotate with the disk 23. As best shown in Fig. 7, the outer extremity of the cup ejector arm 36 extends substantially beyond the periphery of the disk 23 and when positioned as shown in Figs. 7 and 8, is adapted to engage the operative lever 17 associated with the cup holder 15. Accordingly, as the cup ejector arm 36 is moved counterclockwise (as viewed in Fig. 8) to overcome the tension of the retrieving spring of the cup dispensing unit, the operating lever 17 is pushed to the left. When the lever 17 arrives at the end of its throw and the cup dispensing operation has been effected to select and discharge an individual cup in the conventional manner therebelow, the retriever spring will restore the lever 17 to its normal position, acting on the arm 36 to rotate the disk 23 to cause the locking pin 29 to enter the groove 26 and again obstruct turning of the shaft 20 as explained above, until another coin is deposited in the coin chute. The periphery of the disk 23 is provided further with

5 a ratchet section 38 for cooperation with a pawl 40 pivoted at 40° on an ear 41 projecting laterally from one corner of the mounting plate 21. A spring 42, as will be seen from Figs. 8 and 9, 10 is adapted to maintain the pawl 40 in a direction to let the ratchet section 38 slide past the pawl 40 in either direction of rotation of the disk 23 yet will positively cause the pawl 40 to become 15 jambed in a tooth of the ratchet section 38 if it is attempted to reverse the direction of movement of the ratchet section intermediate the start and completion of movement thereof in one direction or the other. Thus after initiation of a 20 cycle of operation of the cup ejector arm 36, reverse movement of the arm 36 is stopped and any attempt to obtain more than a single cup for a single coin will be effectively obstructed by the coacting pawl and ratchet mechanism provided.

25 In connection with the fluid dispensing units as contemplated by this invention, the same is illustrated as applied to a liquid receptacle or bottle 50 adapted to house a predetermined bulk quantity of the fluid to be dispensed. The bottle 50 is supported in inverted position, as shown in the drawings, on a bracket 51 suitably attached to a second bracket arm 52 secured by screws 53 or the like to the frame 10 as shown in Fig. 11. The bracket 51 includes an upright cup member 30 or valve block 54 into which the neck and mouth of the bottle 50 may be seated, there being a gasket 55 of rubber or the like interposed between the shoulder of the bottle and the cup 54 to furnish a cushion as well as a tight seal therebetween. The contents of the bottle 50 are 35 discharged through a pipe 56 which in turn discharges into a cup (such as the cup obtained from the cup dispensing unit) which may conveniently be disposed in a position below the outlet of the pipe 56.

40 An air supply pipe 57, communicating with an opening on the outside of the cup or valve block 54 and extending upwardly within the bottle 50 above the normal maximum level of the liquid therein, serves as a suitable air vent for proper discharge of the bottle contents.

45 In order to provide a control of the fluid passing through the dispensing line, I provide a control valve, which in the present instance, I preferably place in the dispensing line immediately 50 at the outlet of the cup 54. This valve comprises a tapered plunger 58 mounted for sliding movement in a lateral port intersecting the vertical port in the dispensing line, which plunger 58 is 55 adapted to move into and out of fluid obstructing relation to shut off and open the fluid discharge. The projecting end of the plunger 58 is provided with a forked stem 59 between the inner sides of which a downwardly projecting arm 60 of a 60 rocking lever or bell crank may swing in a plane aligned with the axis of the plunger 58. The crank or lever is pivoted as at 61 on an upright ear 62 formed on the bracket 51. Clockwise rotation of the lever 60 causes the end thereof to engage a stop pin 63 at the outer end of the plunger stem 59, thus forcing the plunger 58 outwardly in position to clear the liquid port. Reverse movement of the lever 60, of course, permits the plunger 58 to return to port closing 65 relation or position in the dispensing line. A spring 64 connected to a stop lug 66 on an extending arm 67 of the lever 60 and anchored as at 68 on the bracket 51, is adapted to urge the lever 60 in position to maintain the liquid dispensing line closed by the plunger 58. Opening of

the line is effected by means of a timing bar 70 secured to a piston 71 coacting with a dash pot cylinder 72 secured as at 73 to the bracket arm 52. The bar 70 is provided with a horizontal foot member 75 having a cam portion 76 which is adapted to travel in a path obstructed by a pawl 77 carried at the free or projecting end of the arm 67 of the lever 60. The pawl 77 is coupled to the arm 67 by a pivot 78 and the stop lug 66, against which the lower edge of the pawl 77 may bear, as well as a spring 79 which permits yielding of the pawl 77 relative to the arm 67 as the timing bar cam 76 passes it on the down stroke, while being positive on the upstroke of said bar, to rock the lever 60 to move the plunger 58 to open the fluid dispensing line. A spring 80 normally raises the timing bar 70, being coupled at one end to the foot member 75 and at the other end to a standard 81 formed integrally with the bracket 51. The upper extremity of the timing bar 70 is provided with a locking pin 82 which coacts with a dog or locking latch 83. The dog 83 is pivoted as at 84a on the stationary support or standard 81 for vertical swinging movement to engage and disengage the locking pin 82. When the dog 83 is in engagement with the pin 82, its lower edge is in abutment with a stop 84 on the standard 81, and a spring 85 secured to the dog 83 urges the dog to assume and retain this position.

Operation of the timing bar 70 from an upper position in unlocked relation to the dog 83 to a lower position in locked condition with respect to the dog 83 is controlled through a manually operated member or impeller 90. This member 90 is secured to a slide 91 mounted for up and down sliding movement on a pair of studs 92 cooperating with the edges of slots 93 provided on said slide. The slide 91 is furnished with a handle 94 which is accessible on the outside of the cabinet 12 and the shank of which handle passes through a slot 95 in said cabinet. A spring 96 normally raises the slide 91, being connected at one end to the slide and anchored at the other end to a pin 97 which projects from the rear face of the frame 10. The lower edge or face of the impeller 90 is adapted to engage the upper face of the foot 75 of the timing bar 70, and thereby acts to press the bar 70 from its raised to its lowered position. As the handle 94 is released and the slide 91 begins to rise under the influence of the spring 96, the timing bar 70 remains temporarily locked in lowered position until a bar 98 secured to the slide 91 is carried upwardly sufficiently to trip the dog 83, whereupon the dog 83 is dislodged and the timing bar 70 freed to be lifted under the force of its spring 80, whereupon the cam 76 on the timing bar positively engages and trips the pawl 77 to rock the arm 67 into position to actuate the valve to open the fluid dispensing line. Lifting of the bar 70 under the force of its spring 80 is retarded by its connection with the dash pot referred to. Thus the return of the bar 70 is slow enough to delay reclosing of the valve under varying speeds of rising movement of the slide 91.

A suitable mechanism, such as a needle valve 14, provides means for adjusting the retarding action of the dash pot to suit the time interval during which the valve is held in open position, consistent with delivery and dispensing of a predetermined unit quantity of fluid in the dispensing line.

The impeller 90 is free to operate according to the condition of a locking mechanism in turn

controlled by the coin operated cup dispensing mechanism. More specifically, the locking means comprises a toe 100 normally in obstructing relation or position beneath a bevelled blade 99 on the slide 91, where it prevents the downstroke of the impeller 90. This toe is part of a system of transversely aligned bars 101 mounted for sliding movement in guideways 103 provided on the frame 10. As shown in Fig. 3, an endmost bar 101 is urged by a spring 105 toward the left whereby the endmost of the bars 101 is in positive abutment with a fixed bar 104. In this position, the toe of the bar 101 is in abutment with the end edge of its next adjacent bar 101 and the outer end of the endmost bar 101 is substantially blocked by the edge of an upright locking bar 107, whereby the blade 99 on the slide 91 is positively obstructed. The locking bar 107 is mounted for vertical movement on the front face of the frame 10 and is provided with slots 108 and 109 over the edges of which the heads of studs 110 and 111 are adapted to bear to embrace the bar 107 and furnish a guide therefor. A spring 112 normally raises the bar 107. A pawl 113 is carried by the bar 107, which pawl is provided with a pivot 114, a spring 115 and a stop 117 on the bar 107, in a well known manner to permit the pawl to yield in one direction of rotation of a cam 118 fixed to the shaft 20 of the cup dispensing unit, while being positive to engage and follow rocking movement of the arm or cam 118 when the latter is rotated in a direction to depress the bar 107. When the cam 118 is rocked to complete a stroke effective to cause operation of the cup dispensing unit, it is returned to engage the pawl 113 thus causing the bar 107 to be depressed as shown in Fig. 4. The bar 107 is locked in this position by means of a dog 120 pivoted as at 121 on the bar 107 adapted to become engaged under a locking pin 122 under the influence of a spring 123 and a stop 124. When thus locked in this position by the dog 120, a recess 125 in the bar 107 is disposed in alignment with the end of the latch bar 101. Under these conditions, the bars 101 may be spread toward the right to clear the path of a blade 99 on the slide 91 for operating the liquid dispensing mechanism. It will be observed from Fig. 5 that on such spreading of the bars 101 that a pin 126 on the endmost bar 101 is advanced into a position to trip the dog 120 clockwise and dispose the engaging end of the dog in over center relation to said locking pin 122. As a consequence, when the handle of the impeller is released and the blade on the slide 91 is freed to rise clear of the bars 101, the bar 107 automatically rises under the force of its spring and restores the bar 107 to a position for blocking the bars 101 and the fluid dispensing mechanism is thus locked in operative condition.

One edge of the slide 91 is further provided with a ratchet toothed segment 125a which coacts with a pawl 126a pivoted as at 127 on the frame 10. A spring 128, as will be observed from Fig. 6 for example, will permit the pawl 126a to ride across the ratchet in a continuous path in either direction of travel of the slide 91, yet will positively lock the slide against movement when it is attempted to reverse the direction of the slide movement before a full stroke has been completed. Thus unauthorized "pumping" of the liquid dispensing mechanism is prevented by the ratchet and pawl arrangement which is contemplated herein.

In order that a person patronizing this dispensing unit may tell at a glance whether or not the desired fluid is available, a flag or signal arm 130 is pivoted as at 131 near the top of the frame 10 and directly in line with a window 132 in the housing. The arm 130 is urged by a spring 133 to hold said arm in an upright position (as per dotted lines of Fig. 6) so that it may be viewed through the window aforesaid. The following described escapement mechanism is provided for the purpose of releasably securing the signal arm in a horizontal position below said window until all the liquid in the bottle has been dispensed and for automatically releasing the arm. Slidably mounted on the back of the frame 10 for movement in a path extending directly below the flag 130 when in horizontal position is a register bar 134. Referring particularly to Fig. 6, it will be seen that studs 135 cooperating with slots 136 in said bar provide means for guiding and embracing said bar, and a spring 137 secured to the bar as at 138 and anchored to a pin 139 projecting from the frame 10 acts to normally hold the bar in downwardly urged position. In connection with the operation of this register bar, means are provided for raising it toward the flag arm in step by step system, each step corresponding with a predetermined unit of liquid dispensed. In the present instance I have provided a ratchet 140 on one edge of said register bar, which ratchet comprises notches arranged equidistantly along the edge of the bar and corresponding in selected unit measurement of volume so that the movement of the bar from one notch to the next notch represents an operation of dispensing a single unit volume of the liquid, such as five cents worth of liquid to be dispensed. Mechanism for actuating the bar upwardly step by step comprises a pusher 141 and a locking pawl 142. The pusher is rotatively and slidably disposed upon vertically aligned pivots 143 and 144, which pivots are preferably arranged in direct alignment with the path of movement of the impeller 80. The nose of the pusher is urged upwardly and inwardly about said pivots toward and in engagement with said register bar ratchet 140 by means of a spring 145 connected at its ends as at 138 and 147. The pawl 142 is pivoted at 148 for engaging a notch in the ratchet 140 upwardly of the notch engaged by the pusher 141, a spring 149 connected as at 150 to said pawl and at its other end to the pin 139, acts to urge said pawl into engagement with said ratchet. Thus when the pusher operates to engage a subjacent notch in the ratchet, the pawl 142 holds the register bar against downward movement under the influence of its spring 149. An adjustable contact screw 151 carried by the pusher 141 is adapted to be pressed by the foot member 75 of the timing bar 10 when the latter is operated to complete a fluid dispensing cycle, with the result that the pusher 141 is depressed a distance relative to its pivots sufficient to engage a subjacent notch in the ratchet when released from the force of said timing bar foot member 75 and permitted to be retrieved upwardly by its spring 80. The upper extremity of the register bar is preferably provided with a tapered extension 152 adapted, upon the bar's reaching the limit of its upstroke as determined by the ratchet and corresponding to a position indicating that the liquid storage has been completely used up, to trip a spring pressed latch 153 to release the signal flag, whereby the signal arm is rocked to a ver-

tical position in front of the window 132 under the force of the spring associated with the signal arm.

The apparatus contemplated by this invention further provides a coin operated mechanism wherein the coin may be returned to the operator under certain conditions. For example, if the patron in choosing a particular fluid or product, finds after depositing the coin that the corresponding dispensing line signal denotes "Empty," the cup dispensing shaft prior to the interval that the coin has been turned radially past the locking pin 28, may be rocked counter-clockwise, i. e., in a direction reverse to the direction of operation for initiating a cup dispensing cycle, causing the chute 28 to assume a position as shown in dotted lines in Fig. 8 to dump the coin into a suitable "coin return" accessible to the patron. It will be observed that the length of the groove 26 is such that the locking pin 28 will not engage the shoulder of the groove 26 until the coin is in a position ready to be tipped into such "coin return."

In addition to being operative in a reverse or counter-clockwise direction to return a coin to the operator, as described above, the cup dispenser shaft is effective during such reverse operation to actuate the usual ejector mechanism of the coin receiving apparatus. This is accomplished by means of a link 160 having a lost motion connection as at 161 with the operating lever of said ejector mechanism so as to be ineffective during clockwise rotation of said shaft 28 but positive to actuate the operating lever aforesaid when rotated in a counter-clockwise direction.

Obviously the invention referred to is susceptible of embodiment in forms other than that which is illustrated in the accompanying drawings and described herein, and is applicable for various uses and purposes other than as detailed, and it is therefore understood that this invention contemplates all such modifications and adaptations and other uses of the form of the device herein described, as fairly fall within the scope of this invention.

What is claimed is:

1. In a fluid dispensing apparatus the combination of a fluid container having an inverted outlet to permit flow of fluid therefrom by gravity, a valve block in communication with the outlet, said valve block having a vertical port and a lateral port, the first port opening to the fluid container and the lateral port, a reciprocable valve in the lateral port, a rockable lever coacting with said valve to move said valve to port opening position, a pawl carried by said lever, a depressible member adapted to travel in a path obstructed by said pawl, said pawl being mounted to permit it to yield relative to the lever on the downward stroke of said depressible member and being positive on the upstroke of said depressible member to actuate said rockable lever in a direction effective to move said valve to port opening position, a manually operated member having vertically spaced spaced cams and adapted to be moved from an initial position to an advanced position, means on said depressible member adapted to engage with one or said cams to move said depressible member downwardly, a dog pivoted on a stationary support adapted to hold said depressible member in depressed position, said dog being adapted to be struck and dislodged by the other of said cams on said manually operated member dur-

ing return movement of the latter from advanced to initial position to free the depressed member for movement upwardly to actuate said rockable lever, and means for controlling the upstroke of said depressible member at a constant speed.

2. In a fluid dispensing apparatus the combination of a fluid container having an inverted outlet to permit flow of fluid therefrom by gravity, a valve block in communication with the outlet, said valve block having a vertical port and a lateral port, the first port opening to the fluid container and the lateral port, a reciprocable valve in the lateral port, a rockable lever coacting with said valve to move said valve to port opening position, a pawl carried by said lever, a depressible member adapted to travel in a path obstructed by said pawl and having means for urging said member upwardly, said pawl being mounted to permit it to yield relative to the lever on the down stroke of said depressible member and being positive on the upstroke of said depressible member to actuate said rockable lever in a direction effective to move said valve to port opening position, a manually operated member having vertically spaced cams and adapted to be moved from an initial position to an advanced position, means on said depressible member adapted to engage with one of said cams to move said depressible member downwardly, a dog pivoted on a stationary support adapted to hold said depressible member in depressed position, said dog being adapted to be struck and dislodged by the other of said cams on said manually operated member during return movement of the latter from advanced to initial position to free the depressed member for upward movement to actuate said rockable lever, means for controlling the upstroke of said depressible member at a constant speed and a lock for preventing movement of said manually operated member, said lock being operative upon return of said manually operated member to initial position to prevent a subsequent operation of said manually operated member.

3. In a fluid dispensing apparatus the combination of a fluid container having an inverted outlet to permit flow of fluid therefrom by gravity, a valve block in communication with the outlet, said valve block having a vertical port and a lateral port, the first port opening to the fluid container and the lateral port, a reciprocable valve in the lateral port, a rockable lever coacting with said valve to move said valve to port opening position, a pawl carried by said lever, a depressible member adapted to travel in a path obstructed by said pawl, said pawl being mounted to permit it to yield relative to the lever on the downward stroke of said depressible member and being positive on the upstroke of said depressible member to actuate said rockable lever in a direction effective to move said valve to port opening position, a spring for normally maintaining said depressible member in upward position, a manually operated member having spaced cams adapted to be moved from an initial position to an advanced position, means on said depressible member adapted to engage with one of said cams to move said depressible member downwardly, a dog pivoted on a stationary support adapted to hold said depressible member in depressed position, said dog being adapted to be struck and dislodged by the other of said cams on said manually operated member during return movement of the latter from advanced to initial position to

free the depressed member for movement upwardly to actuate said rockable lever, means for controlling the upstroke of said depressible member at a constant speed, and coin controlled locking means effective to prevent operation of said manually operated member after return of said member from advanced to initial position.

4. In a fluid dispensing apparatus the combination of means forming a fluid dispensing line through which liquid is adapted to flow by gravity, a normally closed control valve in said dispensing line, a rockable lever coacting with said valve to move said valve to dispense fluid from said line, a pawl carried by said lever, a depressible member adapted to travel in a path obstructed by said pawl, said pawl being mounted to permit it to yield relative to the lever on the down stroke of said depressible member and being positive to actuate said rockable lever in a direction to effect opening of said valve on the upstroke of said depressible member, a spring for normally maintaining said depressible member in upward position, a manually operated member having spaced cams adapted to be moved from an initial position to an advanced position, means on said depressible member adapted to engage with one of said cams to move said depressible member downwardly on advance movement of said manually operated member, a dog pivoted on a stationary support adapted to hold said depressible member in depressed position, said dog being adapted to be struck and dislodged by the other of said cams on said manually operated member during return movement of the latter from advanced to initial position to free the depressed member for movement upwardly to actuate said rockable lever, means for controlling the upstroke of said depressible member at a constant speed, and coin controlled locking means effective to prevent operation of said manually operated member after return of said member from advanced to initial position.

5. In a fluid dispensing device, the combination of a fluid dispensing line, a normally closed valve in said line, speed controlled valve opening mechanism including an impeller movable from initial position to advanced position, means combining to form an enclosure for limiting access to said valve opening mechanism, said impeller having a handle operable from the exterior of said housing, and normally locked coin releasable means for controlling operation of said impeller including slidable means biased to a position obstructing the path of said impeller, a locking bar movable toward and away from a position obstructing the path of said slidable means and biased to a position obstructing the path of said slidable means, a pivotally mounted latch adapted to releasably lock said locking bar in a position away from a position obstructing the path of said slidable means preparatory to movement of said impeller from initial position to advanced position and return, and operable to release said locking bar for movement to a position obstructing the path of said slidable means upon return of said impeller to initial position.

6. In a fluid dispensing device, the combination of a fluid dispensing line, a normally closed valve in said line, speed controlled valve opening mechanism including an impeller movable from initial position to advanced position, a second fluid dispensing line having a valve and valve opening mechanism including an impeller movable from initial position to advanced position, means combining to form a housing for limiting access to

said fluid dispensing lines and said valve opening mechanism, each of said impellers having a handle operable from the exterior of said housing, and locking mechanism for preventing operation of one of said impellers during operation of the other of said impellers.

7. In a fluid dispensing device, the combination of a fluid dispensing line, a normally closed valve in said line, mechanism for opening said valve including a manually operable impeller movable from initial position to advanced position, a second fluid dispensing line, a normally closed valve in said second line, mechanism for opening the valve in said second line including a manually operable impeller movable from initial position to advanced position in a path spaced from and parallel to the path of movement of the impeller associated with said first named fluid dispensing line, locking means mounted for movement in opposite directions in a path intersecting the paths of movement of said impellers and so arranged that movement of a selected impeller from initial to advanced position operates to move said locking means to a position clear of the path of said selected impeller and simultaneously obstructing the path of the other impeller, and means operable upon return movement of said selected impeller from advanced position to initial position to restore said locking means to a position ob-

structing the path of movement of both impellers.

8. In a fluid dispensing device, a cup dispensing unit, a fluid dispensing line, a normally closed valve in said line, mechanism for opening said valve including a manually operable impeller movable from initial position to advanced position, a second fluid dispensing line, a normally closed valve in said second line, mechanism for opening the valve in said second line including a manually operable impeller movable from initial position to advanced position in a path spaced from and parallel to the path of movement of the impeller associated with said first named fluid dispensing line, locking means mounted for movement in opposite directions in a path intersecting the path of movement of said impellers and so arranged that movement of a selected impeller from initial to advanced position operates to move said locking means to a position clear of the path of said selected impeller and simultaneously obstructing the path of the other impeller, and coin releasable locking mechanism associated with said cup dispensing unit operable to maintain said impeller locking means in immovable position obstructing the paths of movement of both said impellers.
